INDUSTRIAL TRUCK ATTACHMENT

Samuel Weiss, Portland, Oreg.

Application February 19, 1949, Serial No. 77,418

1 Claim. (Cl. 214—66)

1

This invention relates in general to industrial trucks of the end lift or elevating platform type, and relates particularly to an industrial truck of the type described in my U. S. Letters Patent No. 2,169,440, issued under date of August 15, 1939, and my U. S. Letters Patent No. 2,266,348, issued under date of December 16, 1941, both patents being entitled "Industrial Truck."

In industrial trucks of these types an end lift or front hoisting mechanism is mounted at the front of the truck and carries an elevator frame. A pair of lifting arms or prongs are customarily attached to the end lift frame and the load to be lifted or moved by the truck is supported on such arms or prongs. These arms or prongs must be inserted under the load, and, when the load comprises a barrel or crate, the arms of the lifting or hoisting mechanism are generally pushed under the load while the load is being tipped slightly away from the front of the truck. Thus in the moving of barrels with such a truck two men are customarily employed, one of whom tips the barrel slightly and maintains it in the tipped position while the other operates the truck and causes the arms of the end lift of the truck to be pushed under the bottom of the tilted barrel.

The primary object of the present invention is to provide suitable means to be used with an industrial or end lift truck which will enable the loading of the truck to be performed by the operator of the truck alone.

A related object of this invention is to provide a simple and practical attachment for an industrial or end lift truck by means of which the operator of the truck can handle such an article as a metal drum or barrel, for example, quickly and easily and without the necessity of any manual contact with such article.

The nature of the invention and the manner in which the same is employed will be readily understood from the following description in which reference is made to the accompanying drawings.

In the drawings:

Fig. 1 is a front elevation of an end lift truck showing my attachment in place on the same;

Fig. 2 is a side elevation of the end lift truck of Fig. 1, drawn to a smaller scale, illustrating the attachment in use;

Fig. 3 is a corresponding plan view of the end lift truck and attachment, the attachment shown as employed for lifting a pair of metal barrels or drums;

Fig. 4 is a perspective view, drawn to a larger scale, of my attachment;

Fig. 4A is a side elevation of one of the movable load-lifting arms of my attachment;

Fig. 4B is a side elevation of another load-lifting arm in my attachment;

Fig. 5 is a side elevation of a modification of my attachment, which modification may be used when only a single drum at a time is to be lifted;

Fig. 6 is a corresponding plan view of the modified attachment illustrated in Fig. 5 shown in use with a single drum; and

Fig. 7 is a front elevation of the same modified attachment shown separated from the truck and with the drum omitted from this elevation for the sake of clarity.

In the drawings the reference character **10** indicates an industrial truck having the usual end lift or hoisting means which is indicated in general by the reference character **11**. The hoisting means is preferably tiltably mounted at the front end of the truck and includes an elevator frame **12** which is slidably up and down in guide tracks and is attached to lifting chains **13** driven through the medium of mechanism connected with the truck motor and controlled by the operator of the truck.

It is customary in such industrial trucks to have a pair of load-carrying arms hooked onto, or otherwise carried by, the elevator face plate **12**, and to insert such load-carrying arms underneath the load to be hoisted and carried by the truck, as previously mentioned. In my attachment, however, these ordinary load-carrying arms are dispensed with and in place of the same I provide improved load-lifting arms which are so arranged and mounted as to engage and support the particular load without having to be inserted under the load.

40 A transversely - extending arm - supporting member **14** (shown most clearly in Figs. 1 and 4), having a pair of mounting blocks **15** and **16** secured to the rear face thereof, is attached to the top portion of the elevator face plate **12** by bolts or other suitable means. The top portion of the rear face of this arm-supporting member **14** is formed with an integral semi-cylindrical rib **19**. In the form of my invention shown in Figs. 1 to 4 inclusive, three horizontal forwardly extending arms **16**, **17** and **18** are hooked over the member **14** and are slidably, adjustably carried thereon.

These load-lifting arms **16**, **17** and **18** are arranged in the relative positions shown in Figs. 1 and 4. The two outer arms **17** and **18** are simi-

lar and each has an integral top web 22, although these webs extend oppositely, and each arm has an integral back plate 24, (see also Fig. 4A). The back plates 24 are each formed with a top rearwardly extending lip 20 which has a hook-shaped end. The inner face of this hook-shaped portion corresponds to the surface of the rib 19 on the member 13. Thus the two arms 17 and 18 can be hooked over the member 13 and will then be held in parallel, forward-extending position on the member 13 and will also be slidably laterally on the member 13 and rib 19. An integral lug 23 extends upwardly from the top of each lip 20. These lugs are formed with bores through which a rotatable adjusting shaft 25 extends, and the bores of these lugs are threaded to correspond with the oppositely threaded sections of the rotatable adjusting shaft 25. The center arm 16 is also formed with a curved rearwardly extending lip 21 (see Fig. 4B), which similarly extends over the top of the member 13 and around the rib 19, and a lug 26 projecting upwardly from the rear end of this arm 16 has a round aperture through which the rotatable shaft 25 extends. A pair of collars 27 and 28 are secured to the shaft 25 on opposite sides of this lug 26, thus permitting the shaft 25 to rotate in the lug 26 but preventing any axial sliding of the shaft 25 with respect to the center arm 16. A crank handle 29 for rotating the shaft 25 is secured to one end of the shaft.

Thus the arms 16, 17 and 18, together with their connecting shaft 25, are removably mounted on the member 13, and, when so mounted, the spacing between each of the arms 17 and 18 and the center arm 16 can be adjusted by rotating the shaft 25.

The manner in which my attachment when made in the form thus far described, operates, when the truck is employed, for example, in the moving of steel barrels or drums, will be apparent from Figs. 2 and 3. A pair of such steel barrels or drums are indicated at 30 and 31. Metal drums of this type are customarily made with a cylindrical wall which is deformed with one or more annular outwardly pressed ribs. A pair of such ribs are shown at 32 on the drum 30 in Fig. 2. With my attachment made as previously described it is possible to lift and move a pair of identical drums at the same time when these drums are placed side by side on the ground or on the tops of other drums or crates. Preparatory to engaging a pair of such drums the arms 17 and 18 are adjusted by means of the crank handle 29 until the space between each arm 17 and 18 and the center arm 16 is equal approximately to the outside diameter of the cylindrical wall of a drum to be moved.

The elevator frame 12 with my attachment mounted thereon and the lateral spacing of the arms adjusted as mentioned, is then raised or lowered by the truck operator until the three arms 16, 17 and 18 are below the level of the top rib on the wall of each drum. With the arms at this level the truck is maneuvered and moved forward into engagement with the drums so that the arm 16 will be pushed between the two drums while the arms 17 and 18 will be pushed over the outer side of the drums respectively, until the transverse member 13 comes into contact with the drums. The elevator frame is then raised causing the arms to slide up on the cylindrical wall surfaces of the drums until the arms encounter the ribs on the drums, whereupon continued raising of the elevator frame will cause the

drums to be lifted by the arms and thus supported entirely by the end lift of the truck.

To aid in holding the drums steady while they are supported in this way by the arms 16, 17 and 18, I provide a bottom rest consisting of a lateral bar 33 having inwardly off-set ends 34 which are bolted or otherwise secured to the elevator frame 12 at a spaced distance below the transverse member 13 so as to cause the bar 33 to be mounted in horizontal position for engagement with the bottom portion of the walls of the drums when the drums are lifted by the arms, and thus aid in holding the drums steady while supported on the arms.

When only a single drum is to be removed from a position within a row of drums the arms 17 can be removed from my attachment and the attachment then used with a pair of arms only. However, when the moving and transporting of such drums is ordinarily to take place one at a time, I prefer to employ my attachment in the modified form illustrated in Figs. 5, 6 and 7.

Referring to Figs. 5, 6 and 7, a transversely-extending angle iron 35 is bolted to the elevator frame 12 near the top, in place of the member 13 previously described. This angle iron member 35 is formed with a pair of integral brackets 36 near its ends, which brackets in turn support a transversely-extending arm-carrying shaft 37. A center bracket 38, integral with, or rigidly secured to, the angle iron 35, also aids in supporting the center portion of the shaft 37 and carries a set screw 47 to hold the shaft 37 against any inadvertent axial movement in its supporting brackets.

A pair of load-lifting arm assemblies are mounted on the shaft 37. Each arm assembly comprises a mounting bracket having a face plate 39 (Fig. 5), a top web 40, an integral sleeve 41 (Fig. 6) slidable on the shaft 37, and an upwardly extending arm terminating in a sleeve 42. The load-engaging arm portion of each assembly comprises a forwardly-extending arm 43 which is welded to a base plate 44, and which base plate 44 in turn is securely bolted to the face plate 39 of its mounting bracket.

A threaded positioning shaft 45 extends through and is supported by the pair of upper sleeves 42. Cooperating threaded position-adjusting collars 46, mounted on the shaft 45, as shown in Figs. 6 and 7, enable the pair of extending arms 43 to be set at any desired distance apart. Thus the extending arms 43 can be so set that the distance between their opposed faces will be approximately equal to the exterior diameter of the cylindrical wall of a drum of standard size such as the drum 48 in Figs. 5 and 6. With the extending arms 43 thus adjusted and set the desired distance apart, the lifting, transporting, and placing of such a drum can be done quickly and easily, in the same manner as previously described, by the operator of an end lift industrial truck without requiring the operator to leave his position on the truck.

While this specification thus far has described my invention as employed in the handling of metal drums, and this use constitutes a very important one for my industrial truck attachment inasmuch as the handling of heavy metal drums in warehouses, docks, etc., even with modern industrial trucks, has always involved a considerable expenditure of time and labor, nevertheless it will be obvious that my attachment may also be used similarly on other objects, in particular, crates and boxes having cleats or side ribs on the vertical side walls and thus suitable for engagement by the adjustable arms of my industrial truck

attachment. Obviously also, modifications could be made in the actual construction of the members of my attachment without departing from the principle of my invention, but the forms in which I have shown my attachment have proven very satisfactory in actual operation.

I claim:

In an industrial truck having an end lift, an elevator face plate on said end lift, a transversely-extending arm-supporting member removably secured to said face plate at a slightly spaced distance in front of said plate, said member having a rib extending longitudinally along the upper portion of its rear face, a plurality of arms adapted to be movably and removably supported on said member and when so supported to extend forwardly from said member and from said lift face plate, a back plate on each of said arms adapted to bear against the front face of said member, a hook-shaped lip on the back plate of each arm so shaped as to extend over the top of said member and over said rib so as to support the arm on said member, a bracket lug extending upwardly from each back plate, a screw-threaded arm-adjusting shaft extending through and entirely supported by said bracket lugs of said

10

arms, threaded bores in said bracket lugs for said shaft, and means carried on an end of said shaft for manually rotating the shaft in said bores to adjust the relative spacing between said arms, whereby said arms, with said adjusting shaft connecting them, can be readily mounted on or demounted from said member.

SAMUEL WEISS.
